UNITED STATES PATENT OFFICE.

GOTTLÖB FUEGEL AND HERMAN SCHMID, OF BROOKLYN, NEW YORK, ASSIGNEES, BY
MESNE ASSIGNMENTS, TO APOLLO MAGNETO CORPORATION, OF BROOKLYN, NEW
YORK, A CORPORATION OF DELAWARE.

CLOSURE.

1,386,101.

Specification of Letters Patent.

Patented Aug. 2, 1921.

Application filed August 30, 1919. Serial No. 320,914.

To all whom it may concern:

Be it known that we, GOTTLÖB FUEGEL and HERMAN SCHMID, who were formerly subjects of the German Empire, but who have severally renounced all allegiance to said power and declared our intentions of becoming citizens of the United States, residing in Brooklyn, in the county of Kings and State of New York, have invented certain new and useful Improvements in Closures, of which the following is a specification.

Our invention relates to an improved closure; particularly a closure for covering the openings of passages or ducts by which oil can be supplied to machines to lubricate the moving parts of same. An object of our invention is to provide a closure which is simple in construction and capable of being easily and cheaply manufactured; and which 20 can be easily moved to afford access to the opening, and yet normally be held in closed position.

This object and other objects and advantages of our invention are set forth at 25 length in the following description, which is to be taken in connection with the accompanying drawings; and the characteristics of our invention are precisely defined in the appended claims. We do not wish, however, 30 to be restricted to the exact structure disclosed herein but reserve the right to make changes as regards the shape, size and arrangement of the parts without departing from the spirit and scope of our invention 35 as the same is indicated by the broad meanings of the terms in which the claims are expressed.

On the drawings:

Figure 1 is a side view of a closure according to our invention;

Figs. 2 and 3 are top and bottom views of same;

Fig. 4 is a sectional view taken longitudinally through a closure of the type shown in Figs. 1, 2 and 3, illustrating the latter mounted over the entrance to an oil duct; and

Fig. 5 is a top plan of the structure shown in Fig. 4.

50 The same numerals identify the same parts throughout.

The closure is indicated on the drawings by the numeral 1. It has a flat body with a pair of spaced apart parallel arms 2 ex-

tending from one end, these arms being in 55 line with the lateral edges and being perforated to provide lugs, whereby the closure can be mounted on a pivot pin and moved to open or closed position as desired. The upper face of the closure is flat but the lower 60 or inner face is recessed out somewhat to provide a space for a flat spring 3. This spring is held to the body by means of a rivet 4, and extends from the rivet at one end to the arms 2 at the other end, lying between the latter. This spring is curved adjacent the end between the arms 2; that is at the end which is opposite the riveted end; and it is bent between the arms in the manner indicated in Fig. 1, that is to say it is 70 set so that when the closure is held in the position presented by Fig. 1 the bent or curved end of the spring will extend across the edges of the openings in arms 2 and preferably adjacent the lower parts of these 75 openings. When the closure is mounted in position with a pivot pin engaging the holes in the arms 2, the spring 4 will be disposed so as to rest on top of this pin and thus be put under stress, which makes it hold the 80 opposite end of the closure down tight so as to cover the opening over which it is placed.

In practice, the part of the machine with which the closure is used, the part being indicated at 5, is provided with a pair of perforated lugs 6. Adjacent these lugs and between same, is a recess 7 from the bottom of which leads a passage 8. The closure is mounted in position to cover the recess 7 by passing a pin 9 through the lugs 6 and the 85 perforations in the arms 2; the end of the spring 3 opposite its riveted end, resting upon the top of the pivot pin 9 and thus holding the closure down so as to cover the recess 7 entirely. Oil supplied to the recess 90 7 of course runs down through the passage 8 to the moving parts of the machine; and whenever the supply of oil is to be renewed, the operator merely lifts the closure with his thumb-nail, thus exposing the recess 7; and 100 when the closure is released, the spring 3 forces it down again into covering position.

The body of the closure is preferably cast in one piece and the spring 2 attached by 105 riveting; the operation of riveting being very easy and enabling the closure to be quickly completed. This closure is espe-

cially designed for oil openings for magnetos for internal combustion engines, but might be employed on other constructions as well.

Having described our invention, what we believe to be new and desire to secure and protect by Letters Patent of the United States is:

A closure for an oil opening, comprising a body having a pair of arms spaced apart 10 and extending parallel to each other from one end of the body, said arms having perforations to receive a pivot pin, the closure

being recessed on its lower or inner face; and a spring secured to the said recessed face and projecting between said arms, said 15 spring being curved between said arms and extending across the edges of the openings therethrough.

In testimony whereof, we have signed our names to this specification this 22nd day 20 of May, 1919.

GOTTLOB FUEGEL.
HERMAN SCHMID.
